P. H. FARRELL

PAVEMENT

Filed Feb. 4, 1919

FIG. 1

FIG. 2

FIG. 4

FIG. 3 9 5 2

Inventor

Patrick H. Farrell

By

Patrick H. Farrell

Attorney

UNITED STATES PATENT OFFICE.

PATRICK H. FARRELL, OF TOLEDO, OHIO.

PAVEMENT.

Application filed February 4, 1919. Serial No. 274,877.

To all whom it may concern:

Be it known that I, PATRICK H. FARRELL, a citizen of the United States of America, residing at Toledo, Lucas County, Ohio, 5 have invented new and useful Pavements, of which the following is a specification.

This invention relates to sectional pavements.

This invention has utility when incorporated in removable sections of block pavement, especially as units adjacent special track work, as in intersections and switches. 10

Referring to the drawings:—

Fig. 1 is a plan view of a track intersection for street railways showing in places units incorporating features of the invention therewith; 15

Fig. 2 is a perspective view of a fragmentary unit showing its mounting in relation to a rail; 20

Fig. 3 is a perspective view in fragment, showing the frame and portions of the pavement section unit; and

Fig. 4 is a detail in section showing the 25 mounting of the unit in position.

The railway track is shown as a rail having a ball 1, upstanding web portion 2, and base flange 3. These rails may be mounted in position in various ways as found desirable, 30 for instance, in ties, imbedded in concrete.

The pavement unit, in accordance with the invention herewith, may conveniently comprise base supporting girders or planks 35 4, upon which the platform or base proper 5 may be fixedly mounted as by nails or bolts. This platform 5 of a contour and dimensions desirable for the insertion of the unit especially between track sections, may 40 carry thereon preferably wood paving blocks 6 which may be anchored thereto in spaced relation as to each other by nails 7 toe-nailed or driven at an angle through the block sides into the pavement unit base portion 5. These nails may be driven into the block from one side only.

Integral lugs 8 maintain the blocks in spaced relation in their grain-up position, while the nailing of the blocks in one side 50 only permits of the expansion or adjustment of the blocks relatively to each other on the unit, base or platform. Bolts 9 through the overlapping joist portions 10 of the edge-wise disposed plank members 11 may effectively anchor the frame or board portions 55 11 in the form of a frame about the blocks

6 on the pavement base 5. This completed frame unit is accordingly in position to be installed on the job according to the dimensions of the space to be filled thereby. 60

In the handling of pavements about track work, the pounding of traffic on the rails has a decided tendency to disturb the rail foundations and likewise the pavement.

Unequal settling and working in of moisture with the freezing or expansion tends to disintegrate the pavement, or there is track trouble to be cared for at various times necessitating access to the track or rails for working with the foundation which involves 65

the taking up of the pavement, and in the usual mode of laying pavements by blocks or sheets, there is destruction or such a waste of material, that this repair problem is one involving considerable loss of time 70

and material. In the provision of the unit, as herein disclosed, such unit may be readily placed in position and will remain placed as a good and serviceable pavement unit. 75

In the occasion of repair for the base or for care of the rails, this unit may be removed as a unit, and is not destroyed but may be placed back into position when the repair work or investigation or inspection has had attention. 80

This unit has a special utility or value when disposed between rails, but may to advantage be used adjacent rails or the special work, and track units for availing of this advantage of pavement unit removal 85

and thereby avoid destruction of paving blocks in gaining access to the track or track base.

The unit as to its base and frame may conform to the space in which it is to be installed, while it may be mounted upon the foundation supporting the rails and the ties, it is preferably mounted in the position to be carried by the flanges of the rails, especially on the side toward the rails. This 90 means that the unit will be at all times maintained in position as to the rail.

The unit as to its base and frame may conform to the space in which it is to be installed, while it may be mounted upon the foundation supporting the rails and the ties, it is preferably mounted in the position to be carried by the flanges of the rails, especially on the side toward the rails. This 95 means that the unit will be at all times maintained in position as to the rail.

In installing the unit it has sufficient clearance as to the rail that the unit may be placed in position without difficulty. When 100 installed this slight space may be filled by crushed stone, or other desired materials, which upon the removal of the unit may be taken out as found convenient.

In practice these units may be made up 110 in the same manner that the track sections are made up and shipped to the job for

installation on the pavement base, thereby meaning a minimum of interruption of traffic in the installation of the pavement. For removal of the units, clearing out of a portion or portions of the clearance space may permit use of bars or grapple-hooks from a derrick in lifting the unit out.

What is claimed and it is desired to secure by Letters Patent is:

- 10 1. A base, paving blocks assembled on said base, said blocks supported by said base, a track provided with a rail having a flange integral therewith upon which flange the base rests on at least one side thereof whereby in track use settling and recovery movement of the rail is followed by the blocks only as held assembled on said base, thereby maintaining the blocks against relative disturbance from rail movement.
- 15 2. The combination with a group of paving blocks, a plank base supporting the blocks, and a frame on the base maintain-

ing the blocks in a pavement unit with said base, of a track provided with a rail having a base flange engaged by the unit base 25 whereby traffic on the rail tending to settle the rail does not disturb the blocks of the unit as to the rail but such blocks as assembled in the unit follow the rail movement up and down.

30 3. A pavement unit comprising a platform of parallel plank, transverse strips therebelow to hold the plank against relative settling, wood paving blocks, nails anchoring the block in abutting relation to 35 each other on said platform, and a frame on said base about the blocks rising to the height of the blocks in completing a pavement wear face uniformly supported against block or frame shifting as to said 40 platform.

In witness whereof I affix my signature.

PATRICK H. FARRELL.
